J. F. HUCKEL

LUNCH COUNTER STOOL

Filed Sept. 13, 1926

UNITED STATES PATENT OFFICE.

JOHN F. HUCKEL, OF KANSAS CITY, MISSOURI, ASSIGNOR TO FRED HARVEY, OF KANSAS CITY, MISSOURI.

LUNCH-COUNTER STOOL.

Application filed September 13, 1926. Serial No. 135,102.

- My invention relates to counter stools and has for its principal object to provide a device of that character which may be permanently anchored in a floor to maintain constant relative arrangement of the stool with a counter or the like, which may be easily erected and assembled and as easily and quickly dismantled should it be desired to remove the stool after its installation.
- 10 In accomplishing these objects I have provided improved details of structure, the preferred forms of which are illustrated in the accompanying drawings, wherein:
- Fig. 1 is a perspective view in central, vertical section, of a counter stool embodying my invention.
- 15 Fig. 2 is an enlarged detail perspective view of part of the pedestal and the seat pintle bushing, in central longitudinal section.
- 20 Fig. 3 is a detail perspective view of a part of the pedestal, the bushing and the seat with its pintle, parts being broken away for better illustration.
- 25 Referring more in detail to the drawings, 1 designates the floor upon which the stool is mounted, either singly or in group, here shown to be constructed of concrete to illustrate adaptation of the stool to modern
- 30 building construction, and 2 an anchor plate embedded in the floor and provided with a vertical threaded aperture 3. 4 designates an anchor rod, the lower end of which is embedded in the floor and threaded into 35 the anchor plate 2 to fix the rod permanently to the floor, the rod rising perpendicularly and terminating slightly below the level of the stool seat in a threaded upper end 5. Fitting over the anchor rod 4 is a pedestal 6, 40 preferably of cast metal, having a tubular standard portion 7, a flared base flange 8 seating on the floor and anchored thereto by a suitable device such as the screw 9, and a flanged upper rim 10 counterbored to form 45 the shouldered seat 11.
- The pedestal standard is provided, near its top, with an inwardly directed flange 12, forming a seat for a pintle bushing 13. The pintle bushing may be chambered throughout part of its length to reduce the bearing surface for the pintle and provide a grease chamber, and has a threaded socket at its lower end whereby it is attached to the top of the anchor rod 4 and drawn snugly 55 against the seat flange 12, the bushing being of sufficient diameter to snugly fit the upper portion of the pedestal and having a flange 14 at its upper end, located within the counterbored seat 11 in the rim flange of the pedestal; the bushing being of such length 60 as to provide support on both the seat flange 12 and shouldered seat 11, and being centrally bored to provide a bearing for the seat pintle 15.
- 16 designates the seat portion of the stool, 65 preferably comprising a cast metal frame of suitable design and provided with in-turned ears 17 to which a spider 18 is removably secured by bolts or the like 19.
- The pintle 15, heretofore mentioned, is 70 fixed to the center of the spider 18 and the spider is provided concentrically with the pintle with a boss 20 constituting the bearing portion of the seat. The pintle is of sufficient length to extend substantially into 75 its bushing in the top of the pedestal and of such diameter that it may rotate in its bearing in the bushing without lost motion, in order that a person occupying the stool may turn freely to and from the counter. 80 To prevent wear on the permanent portions of the structure I interpose one or more fibre or like washers 21 upon the pintle and between the pedestal cap and the boss on the seat spider, so that the seat member does 85 not come into direct contact with the pedestal but is separated therefrom by the washers; consequently rotative movement is between the washers or between the washers and one of the permanent stool members and 90 there is no direct contact of the metal seat spider with the metal pedestal.
- Fitting within the frame 16 is a seat 22, 95 preferably of upholstered, wooden, frame construction to provide a comfortable seat and also adapt the seat for permanent connection with the spider 18, by screws or the like (not shown) which may be projected through apertures 23 in the spider into the wooden members of the seat frame.
- The seat portion of the stool is provided 100 with a back rest 24 comprising standards 25 and a cross member 26, both of which are preferably cast integral with the seat frame 16.
- Assuming the parts to be constructed as 105 described, and the anchor plate 2 located within the floor, it is apparent that the stool may be easily and quickly assembled by projecting the lower end of the anchor rod 110

through an aperture in the floor, provided for that purpose, and threading the lower end of the rod into the embedded anchor plate and fitting the pedestal over the anchor rod and attaching the base flange of the pedestal to the floor by the screw 9. The pintle bushing is preferably assembled with the pedestal at the point of manufacture and the pintle similarly assembled with the seat spider. The spider is preferably attached to the seat frame at the point of erection, and when so assembled may be applied to the pedestal by merely dropping the pintle into its bushing. The seat proper may be attached to the spider within the seat frame after the other parts have been assembled and erected.

With the parts so assembled, a customer may turn the stool so that he can seat himself thereon and then turn the stool about to face the counter, the seat turning readily on its pintle mounting, but the washer support preventing a too free or spinning movement of an unoccupied stool.

It is further apparent that a stool of this construction is economical in manufacture, easily and quickly assembled, and slight in appearance, features that are not to be disregarded in consideration of the employment of such a device.

What I claim and desire to secure by Letters Patent is:

1. A stool of the character described, comprising a tubular pedestal having an interior flange and a shouldered seat at its upper end, a bushing within the pedestal seated upon the interior flange and having a rim flange located in said shouldered seat, a seat member rotatably mounted on the pedestal and having a pintle journaled in said bushing, and a wear member interposed between said member and the pedestal about the pintle.

2. In a stool of the character described, a tubular pedestal having a base flange and a cap flange, the cap flange having an upwardly opening shouldered seat, an anchor plate embedded within the floor upon which the pedestal is supported, an anchor rod within the pedestal and attached to the anchor plate, a bushing in the upper end of the pedestal connected with the anchor rod and having a flange seated in said shouldered seat, a seat member comprising a spider rotatably supported on the pedestal, and a pintle on said seat member, extending into and journaled in the bushing.

In testimony whereof I affix my signature.

JOHN F. HUCKEL.
